Bela A. Mann

UNITED STATES PATENT OFFICE.

BELA A. MANN, OF WEST MERIDEN, CONNECTICUT.

IMPROVEMENT IN LOOMS.

Specification forming part of Letters Patent No. 40,698, dated November 24, 1863.

To all whom it may concern:

Be it known that I, BELA A. MANN, of West Meriden, in the county of New Haven and State of Connecticut, have invented certain new and useful Improvements in Jacquard Looms; and I do hereby declare the following to be a full, clear, and exact description thereof, reference being had to the accompanying drawings, figures, and letters of reference thereon, making part of this specification.

Of the said drawings, Figure 1 is a side elevation, having parts of the frame removed. Fig. 2 is an end elevation showing the pattern mechanism, &c. Fig. 3 is a drawing of the crank and connecting rods detached from the machine. Fig. 4 shows a spring for forcing the hooks upon the driving-gate L. Fig. 5 shows the needles S in detail for operating the hooks. Fig. 6 shows a hooked bar detached from the machine.

Similar letters of reference indicate like parts in all the drawings.

My invention relates to Jacquard loom; and it consists, first, in the employment of hooked bars, in combination with a card prism or pattern apparatus for producing the shed; second, the employment, in combination with the hooks and a pattern mechanism, of gates or slides moving in opposite directions for operating the hooks; third, the arrangement, in combination with the hooks and slides, of the adjustable cranks, for driving the slides; fourth, the arrangement of the series of bell-crank and their connections, in combination with the hooks, slides, and pattern mechanism for operating the harness.

To enable others skilled in the art to make and use my improvements, I will describe the construction and operation thereof.

The drawings, Fig. 1, show a side elevation of my loom without any lathe, and with the frame part A A broken away, to show the working mechanism. The shaft B has proper journal-boxes at C and C', and is provided with a crank-wheel, D. On the other end of this shaft there is a wheel, E, on the back side of which is a plate, U, having a cam groove cut therein for operating the pattern mechanism through the rod J, and lever or arm M. To the face of this wheel E there is bolted a slotted bar, F, into which is inserted the crank-pin W, which, by means of the rod H, and its

connecting-pin Y, works the upper gate or slide, L. To the outer end of the crank-pin W is secured a slotted arm, G, provided with a crank-pin, w, which connects the rod I at r with the lower gate or slide, K, and gives it motion. The gates or slides L and K have V-shaped edges, and fit corresponding V-grooves in the vertical bars 1, which are bolted to the cross-ties 4 and 5, as plainly shown in Fig. 2. Attached to the bars 1 are ears projecting outward, to which is bolted the cross-tie 6, and to these ears is pivoted at 15 the arm-lever M, the rods 7 and 8 being cross-ties which connect with and hold a corresponding vertical arm of the lever M upon the opposite side. In the lower part of this vertical arm M is suspended by pivots 14 a square bar R, in which are cut longitudinal mortises for the needles s to pass through the pattern-cards, and which is provided with conical spurs 9, which enter corresponding holes, 9, in the card-prism to insure the proper position of the card-pattern for the needles s. On one end of this square bar is a pin-gear, 10, Fig. 2, which, by means of the ratchet-finger O, moves the bar R a quarter-revolution at each reciprocating movement of the arm or lever M. The hook-bars N are slotted longitudinally, and work upon a fulcrum-pin, p, passing through ears on the upper gate or slide, L, as plainly shown in Fig. 1. Both ends of each of these hook-bars have a slit cut therein for the reception of the ends of the connecting-wires m and o, which are held therein by pins. To the cross-tie 6, springs t t are secured. Fig. 4, which rest upon the upper part of the hooks to force them upon the gate or slide, L. The upper end of the slide is beveled the shape of the hook 2, Fig. 6, and the lower slide, K, is also beveled through a slot near the lower end to conform to the shape of the hook 3. On this lower gate is cast a projection, a', which is slotted for the connecting wires o, which forces up the hooks by striking the lower ends thereof as the slide K travels.

The needles s, for operating the lower parts of the levers, are plainly shown in the drawing 5, and also in Fig. 1. They are provided with small collars to retain them in the plate P. The harnesses a a are suspended by the wires h and i, which connect them to the bell-crank c and b by the wire k above, and to e and f by the wire n below. There is a

set of bell-crank, *d*, which connect by the wire *l* with the upper ends of the hooks *N* by the rods *m*, and also a set, *g*, which connect by rods *o* with the lower end of the hooks. These bell-crank have their bearings upon rods *Y* and *X* passing through the frame, and are kept in position by collars and set-screws 12 and 13, as shown in Fig. 2.

Operation. The operation will be as follows: The non-perforated card being presented to the needles *s*, and the gates or slides *L* and *K* being open, the cranks *G* and *W* will stand in the position seen in Figs. 1 and 3, and motion being given the shaft in a forward direction, the hooks *N*, as the arm *M* travels, will all be forced by the needles *s* (one end of which rests upon the non-perforated card, while the other rests upon the lower parts of the hooks) from the gate *L*, and consequently hooked onto the lower gate, *K*, and all the harness are drawn upward as the gate *K* moves down, carrying with it all the hooks *N* and drawing all the upper bell-crank forward and all the lower ones back. The next revolution of the shaft and movement of the pattern mechanism will cause all the needles *s* to enter the full perforated card, and all the hooks will be forced by the springs *t* upon the upper gate, *L*, and carried upward, thus reversing the movement of the bell-crank and carrying all the harness down. In all the rest of the movements of the pattern mechanism, as the shaft is revolved, the needles *s*, which do not pass through the holes in the card-prism into the square bar *R*, will release or unhook the hooks *N* from the upper gate, *L*, and the harness operated by such needle and hook will be drawn upward, while those needles that do enter the holes in the card-prism will allow the hooks *N* to remain upon the upper gate, and the harness operated by such needle will be drawn down. When the hooks *N* are released from the gate *L*, they are hooked to the gate *K*, and vice versa.

The pattern mechanism is operated by the cam-groove *U*, into which is inserted a pin, *v*, on the lower end of the rod *J*, and is held in place by the grooved bar *V*. The upper end of the rod is pivoted to the arm *M* at *w*, and as the cam-wheel revolves the rod *J* is forced up and down, and the lever *M* rocked upon its fulcrum-pin 15, and the pattern mechanism is

moved to and from the needles *s*. As the rod *J* is forced up, the horizontal arm of *M* is carried up, and the vertical arm and bar *R* brought in contact with the pins *s*, and as the lower arm of the lever *M* is carried away from the pins *s*, the ratchet-finger *O*, which is pivoted to the part *P*, drops upon a pin, 11, Fig. 2, and gives the bar *R* a quarter-revolution, and presents a new card to the needles at each revolution of the shaft. This square bar is held in position by means of a flat spring, *Z*, secured to the arm *M*, and which rests at its lower end upon the bar holding it for the needles. The cards are linked together and supported in a holder, *T*, as plainly shown. The cranks *W* and *w* are adjustable by means of the slotted arms *F* and *G*, so as vary the travel of the gates *L* and *K*, and thereby regulate the shed for the passage of the shuttle. By moving the crank-pins *W* and *w* from the axis of the shaft, the throw of the shed will be greater, and toward the axis of this shaft the shed will be less.

It will be obvious from an inspection of the drawings and specification that the hooks *N* will never miss catching upon the slides, thus securing a positive motion of the harness and perfect work.

Having thus fully described my improvements, what I claim is—

1. The hooked bars *N*, in combination with a pattern mechanism, substantially as described.
2. The employment, in combination with the hooks *N* and a pattern mechanism, of the slides *L* and *K*, moving in opposite directions for operating the hooks, substantially as described and specified.
3. The arrangement, in combination with the hook-bars *N*, of the adjustable cranks and *W*, for driving the slides *L* and *K*, substantially as described and specified.
4. The arrangement of the bell-crank, in combination with the hooks *N*, slides *L* and *K*, and pattern mechanism, for operating the harnesses, substantially as described and set forth.

BELA A. MANN.
